UNITED STATES PATENT OFFICE

2,048,631

PRINTING PLATE

William T. Motson, Sr., Philadelphia, Pa.

Application July 20, 1934, Serial No. 736,248

1 Claim. (Cl. 101—395)

The present invention is a flexible printing plate.

It is an object of this invention to provide a printing plate of flexible material which may be utilized interchangeably on cylinder or letter presses and in fact any press of the rotary type or of the type which uses flat plates.

It is a further object of the invention to provide a printing plate which may be used interchangeably on cylinder presses of all types regardless of the size of the cylinders.

A further object of the invention is the provision of a novel base or backing for the plate, which base will not only provide a flexible assembly, but will also furnish additional resiliency to the same, whereby objects of various thicknesses may be printed without adjusting the mechanism of the press.

Another object of the invention is to provide a printing plate which will be simple in construction and of low manufacturing cost, yet rugged and convenient in operation and use.

Other objects and advantages of the invention will be apparent from a reading of the following description in connection with the drawing, wherein for the purpose of illustration, I have shown a preferred embodiment of the invention.

In the drawing:

Figure 1 is a perspective view of a printing plate embodying my invention.

Figure 2 is an enlarged sectional view taken substantially along line 2—2 of Figure 1.

Figure 3 is a similar view, but showing the plate as applied to a cylinder press or the like.

Figure 4 is a plan view of a printing plate showing a modification of the invention, and

Figure 5 is a sectional view taken along line 5—5 of Figure 4.

Referring more particularly to the drawing, there is shown therein a flexible printing plate having a flexible printing surface 10, preferably formed of rubber, and a backing 11 of flexible material secured thereto by either cement, or, preferably, by vulcanization under great pressure, whereupon the base and printing surface become integral for all practical purposes.

In the preferred form of the invention, as dis-

closed in Figures 1 to 3, inclusive, the base 11 is formed of a rather stiff yet flexible material consisting in this case of a pair of outer sheets of canvas or the like impregnated with "bakelite" or other condensation product of phenol or the like, as indicated at 13 and 14 and having integrally vulcanized therebetween a sheet of very pliable rubber as indicated at 15.

This form of the invention allows the plate to be used readily upon letter presses because of its semi-rigid assembly, yet provides means for its use upon cylinder presses, also, if desired.

In the embodiment of the invention disclosed in Figures 4 and 5, the printing surface 10 is shown vulcanized to a preferably very heavy fabric which permits of the plate readily being used upon cylinder presses of all sizes, yet provides means for its use with flat type presses.

Both forms of the invention may be secured to the so-called "patent blocks" or wooden backings by means of fastening devices of conventional character.

One of the advantages of this construction is its great adaptability to all types of presses and its capability of use, without fine adjustment, in connections with materials of various surfaces such as, for example, paper, cardboard, textiles, glass, fibre, sandpaper, aluminum products, tin, celluloid, cellophane, corrugated boxes, bakelite products, burlap, asbestos, metals, wallboard, oil cloth, wood and other rough surfaces in one or more colors of ink or dye as used in the printing art.

Though I have shown and described herein the preferred embodiments of the invention, it is to be definitely understood that I do not desire to limit the application of the invention thereto, but any change or changes may be made in the structure or arrangement within the spirit of the invention or the scope of the appended claims.

What is claimed is:

A printing plate formed of rubber and having a backing sheet formed of a pair of fabric sheets impregnated with a phenolic condensation product with a layer of soft rubber therebetween.

WILLIAM T. MOTSON, Sr.
